UNITED STATES PATENT OFFICE.

ALBERT ERICKSON, OF CHICAGO, ILLINOIS, ASSIGNOR TO SPLITDORF ELECTRICAL COMPANY, OF NEWARK, NEW JERSEY, A CORPORATION OF NEW JERSEY.

IGNITION DEVICE FOR INTERNAL-COMBUSTION ENGINES.

1,286,175.

Specification of Letters Patent. Patented Nov. 26, 1918.

Application filed June 8, 1918. Serial No. 239,002.

To all whom it may concern:

Be it known that I, ALBERT ERICKSON, a citizen of the United States, residing at Chicago, in the county of Cook and State of Illinois, have invented certain new and useful Improvements in Ignition Devices for Internal-Combustion Engines, of which the following is a specification, reference being had to the accompanying drawing.

10 The invention relates to new and useful improvements in ignition devices for internal combustion engines, and more particularly to an ignition device of the make-and-break type, wherein the ignition current is supplied by a magneto generator of the plugoscillatory type.

15 The object of the invention is to provide an ignition device of the above character with an oscillating mechanism which can be mounted on the end of the cylinder and operated from the cam shaft or side shaft of the engine.

20 A further object of the invention is to provide an ignition device of the above character, wherein the make-and-break electrodes, the plugoscillator and the oscillating mechanism are all carried by a unitary bracket mounted on the head of the engine cylinder.

25 A still further object of the invention is to provide a mechanism of the above character, wherein the advance and retarding device is also supported on the unitary bracket carrying the other parts of the ignition device.

30 In the drawings which show by way of illustration one embodiment of the invention,

Figure 1 is an end view showing the head of the cylinder with my improved ignition mechanism applied thereto, the magneto generator being removed from the supporting bracket to show the parts in rear of the same;

35 Fig. 2 is a side view of the ignition mechanism with the magneto generator in place;

Fig. 3 is a plan view of the same; and

Fig. 4 is a detail showing on an enlarged scale, the position of the parts when the spring actuating mechanism is tripped from engagement with the push rod.

40 The invention is directed generally to an ignition device having make-and-break electrodes mounted on a bracket attached to the head of the cylinder. Current is supplied 45 to the electrodes from a magneto generator,

preferably of the plugoscillatory type, which is also mounted on said bracket. The generator and the electrodes are operated by a trip actuated mechanism. When the parts are mounted on the head of the cylinder, a 60 new arrangement of devices is necessary in order to actuate the tripping mechanism as the movement of the push rod for operating the same is now in a direction transverse of the longitudinal axis of the cylinder rather 65 than parallel thereto. In order to provide means for operating the spring actuated tripping mechanism when located as stated, I have mounted a swinging or oscillating lever on the supporting bracket for the electrodes and the generator and the push rod is attached to this lever, preferably through a means which permits adjustment of the connection of the rod to the lever for timing purposes. The lever is oscillated by a link 70 connection with a crank on the cam shaft at the side of the cylinder, which shaft is usually referred to as the side shaft of the engine.

Referring more in detail to the drawings, 80 I have shown my invention as applied to an engine having a cylinder 1, the head of the cylinder being shown in Fig. 1 of the drawings. My improved ignition device includes a fixed electrode 2 and a movable electrode 3. The 85 movable electrode 3 is carried by a shaft 4, having a cam finger 5 attached to the outer end thereof. A spring 6 bearing against this cam finger normally holds the electrodes in engagement. The electrodes are mounted 90 in a bracket 7, which is attached to the head of the engine cylinder by suitable bolts. Mounted on this bracket is a spring actuated tripping mechanism which consists of springs 8-8 and a trip-lever 9. Also mounted 95 on the bracket 7 in an integral shelf 10 which carries the magneto generator, indicated at 11 in the drawings. The magneto generator is of the usual construction and on the outer end of the rotor, or armature shaft of the magneto generator, is a 100 forked arm 12, which engages one of the pins 13 of the trip-lever 9, so that the movements of the trip-lever 9 are imparted to the rotor or armature shaft.

105 The trip-lever 9 is actuated by a push rod 14, which is provided with a shoulder 15 adapted to engage an abutment 16 on the trip-lever, so that, as the push rod 14 is moved to the left (as viewed in Figs. 1 and 110

4) it will oscillate the trip-lever 9, placing the springs 8—8 under increased tension and throwing the springs out of alinement. The trip-lever is also provided with a cam projection 17, which engages the push rod 14 and forces the shoulder 15 out of engagement with the abutment, thus tripping the actuating mechanism and permitting the springs as they return to alined position to operate 10 the rotor or armature shaft. The trip-lever is provided with a cam projection 18, which engages the cam finger 5 and separates the electrodes in proper timing for the production of the ignition spark. This particular 15 tripping mechanism, and manner of operating the electrodes, forms no part of my present invention, but is shown, described and claimed in my prior application, Serial No. 182,728, filed July 25, 1917.

20 The present invention is directed particularly to the manner of operating the push rod 14. Mounted on the bracket 7 is a lever 19. Said lever is mounted so as to swing freely about a pivot bolt 20. The push rod 14 is attached to and carried by this lever 19. Said push rod is mounted to turn freely on a projecting pin 21 and is held thereon, as herein shown, by a split key 22. The push rod 14 surrounds a bushing 23, which is eccentric to the pin 21, and this bushing is carried by a finger piece 24, which is capable of adjustment about the pin 21, so as to adjust the position of the push rod 14 for timing purposes. A spring 25 encircles the pin 21 30 and one end of this spring engages the underface of the push rod 14, as indicated at 26. The other end of this spring, as indicated at 27 in Fig. 2, engages the lever 19. This spring tends to raise the outer free end of the 40 push rod and yieldingly holds the same in contact with the trip-lever. The lever 19 at its lower end is pivoted to a link 27. Said lever 19 may be provided with a pivot pin 28 which extends through the end of the link 45 and is held therein by a split key 29. The other end of the link 27 is connected to a crank 30, shown diagrammatically in Fig. 1, as carried by the shaft 31. This shaft 31 is the cam shaft or side shaft of the engine, 50 and said shaft rotates so that the crank 30 moves in a complete circle, the path of which is indicated by the broken line in Fig. 1. As the shaft rotates, this crank will impart an endwise movement to the link 27, which in 55 turn will oscillate the lever 19, thus moving the push rod endwise back and forth and the push rod in turn will actuate the tripping mechanism, moving the trip-lever, carrying the springs out of alinement until the push 60 rod is tripped from connection with the trip lever, and then the springs will operate to oscillate the rotor and separate the electrodes at the proper time for ignition.

It will be noted that the link 27 is made 65 adjustable. Said link has a central part 27^a,

which has a right and left-hand threaded connection with the other parts of the link and this section 27^a may be removed and other sections substituted therefor of different lengths, so that the actuating mechanism 70 for the ignition device is readily adjustable to adapt the same to engines of different sizes.

It is obvious that minor changes in the details of construction and arrangement of the parts may be made without departing from 75 the spirit of the invention, as set forth in the appended claims.

Having thus described my invention, what I claim as new and desire to secure by Letters Patent, is:

1. An ignition device comprising ignition electrodes, a generator, spring operated mechanism for actuating the electrodes and generator, a push rod for tripping the said actuating mechanism, a vibrating member 25 supporting and operating said push rod, and a link connected to said vibrating member and adapted to be reciprocated from the rotating side shaft of the engine.

2. An ignition device comprising ignition 90 electrodes, a generator, spring operated mechanism for actuating the electrodes and generator, a bracket adapted to be connected to the head of the cylinder and supporting the electrodes, the generator and the operating mechanism, a push rod for tripping the actuating mechanism, means carried by the bracket for supporting and operating the push rod, and devices for operating said means from the side shaft of 100 the engine.

3. An ignition device comprising ignition electrodes, a generator, spring operated mechanism for actuating the electrodes and generator, a bracket adapted to be attached 105 to the head of the cylinder and supporting the electrodes, the generator and the operating mechanism, a push rod for tripping the operating mechanism, a lever pivotally mounted on said bracket and supporting 110 and operating said push rod, and means for oscillating the lever from the side shaft of the engine.

4. An ignition device comprising ignition electrodes, a generator, spring operated 115 mechanism for actuating the electrodes and generator, a bracket adapted to be attached to the head of the cylinder and supporting the electrodes, the generator and the operating mechanism, a push rod for tripping the 120 operating mechanism, a lever pivotally mounted on said bracket and supporting and operating said push rod, and means for oscillating the lever from the side shaft of the engine, said means including a link having 125 adjustable and interchangeable parts whereby the ignition device may be readily adapted for engines of different sizes.

5. An ignition device comprising ignition electrodes, a generator, spring operated 130

mechanism for actuating the electrodes and generator, a bracket adapted to be attached to the head of the cylinder and supporting the electrodes, the generator and the operating mechanism, a push rod for tripping the operating mechanism, a lever pivotally mounted on said bracket and supporting and operating said push rod, means for oscillating the lever from the side shaft of the engine, said push rod being pivotally connected to said lever, and a spring supported by the lever for normally holding the push rod in engagement with said operating mechanism.

6. An ignition device comprising ignition electrodes, a generator, spring operated

mechanism for actuating the electrodes and generator, a bracket adapted to be attached to the head of the cylinder and supporting the electrodes, the generator and the operating mechanism, a push rod for tripping the operating mechanism, a lever pivotally mounted on said bracket and supporting and operating said push rod, and means for oscillating the lever from the side shaft of the engine, said push rod being connected to said lever through adjustable devices which permit the position of the push rod relative to the lever to be varied for timing purposes.

In testimony whereof I hereunto affix my signature.

ALBERT ERICKSON.
